(57) **CLAIM**

The ornamental design for a “cap for fluid container,” as shown and described.

DESCRIPTION

FIG. 1 illustrates an isometric view of a cap for a fluid container of the present invention.

FIG. 2 illustrates a first side elevation view of the cap of the present invention.

FIG. 3 illustrates a second side elevation view of the cap of the present invention.

FIG. 4 illustrates a front plan review of the cap of the present invention.

FIG. 5 illustrates a rear plan view of the cap of the present invention.

FIG. 6 illustrates a top plan view of the cap of the present invention; and,

FIG. 7 illustrates a bottom plan view of the cap of the present invention.

The broken lines in the drawings represent environmental subject matter and form no part of the claimed design.
